WATER-JET HYDROFOIL BOAT

Calvin A. Gongwer, Glendora, Calif., assignor to Aerojet-General Corporation, Azusa, Calif., a corporation of Ohio

Filed Jan. 7, 1963, Ser. No. 249,768
7 Claims. (Cl. 114—66.5)

This invention relates in general to fluid intake means useful with water craft, and in particular to combined structure and intake means.

There have been many recent advances in propulsion means for small craft. In particular, emphasis has been placed on the use of hydrofoils to increase the speed of such craft far beyond that attainable through attempting to drive smaller size vessels through water with their hulls partially immersed. Hydrofoils have to date provided the support necessary to lift a hull and its contents, whether passenger or cargo, from the water and to permit motion through the water with much less friction than is present when the hull is partially immersed.

Hydrofoil advances to date have been concentrated on reaching an optimum shape of hydrofoils and their disposition with respect to the hull of the craft. All known hydrofoils are fixed or rigid with relation to the craft, or at the most adaptable for movement about a single axis of the support surface itself depending on the amount of lift desired.

With the development of fluid jet propulsion, that is, water-jet propulsion such as produced by the device disclosed in my copending U.S. patent application Serial No. 20,897, filed April 8, 1960, now abandoned, which is assigned to the same assignee as the present invention, such improved propulsion means give promise of improved speed in hydrofoil craft. With the use of a device for providing water-jet propulsion there is a necessity for inducing water into the vessel, or to the jet-producing device itself, while the hull of the craft is above the surface of the water from which the craft receives support.

All hydrofoil vessels suffer drag and weight penalties due to the requirement that a provision be made for propulsion appendages such as propeller, shafting, struts, gear boxes, or in the case of water-jet propulsion, water scoop and ducting, all of which cause drag proportionately larger than the low drag typical of hydrofoil supports alone. To avoid such penalties, the intake means of the present invention have been devised.

It is, accordingly, an object of this invention to provide means for inducting water into a craft or other vessel of the hydrofoil type powered by water-jet propulsion which does not entail the use of appendages from the vessel or craft other than those normally installed.

It is another object of the present invention to provide for the intake of water by a craft or vessel powered by water-jet propulsion wherein the intake conduit is combined with other structural members of the craft or vessel.

It is a further object of this invention to provide means for the intake of water into a craft or vessel powered by water-jet propulsion wherein the hull of the vessel during normal operation is above the surface of the water.

Other objects and many of the attendant advantages of this invention will be readily appreciated as the same becomes better understood by reference to the following description when considered in connection with the accompanying drawings, wherein:

FIG. 1 is a plan view, schematic in form, of a craft illustrating one embodiment of the invention.

FIG. 2 is an enlarged cut-away longitudinal sectional view of a portion of one of the hydrofoils of the embodiment of FIG. 1.

2

FIG. 3 is a transverse section of the hydrofoil shown in FIG. 2 taken along line 3—3 thereof.

FIG. 4 is a side elevational view, schematic in form, of the embodiment illustrated in FIG. 1.

5 FIG. 5 is an enlarged sectional view, partially shown in elevation, of a support member of the embodiment illustrated in FIGS. 1 and 4.

10 FIG. 6 is a front end elevational view, schematic in form, of a craft illustrating a second embodiment of the invention.

15 FIG. 7 is a side elevational view, schematic in form, showing the hydrofoils of the embodiment of FIG. 6.

FIG. 8 is an enlarged longitudinal sectional view of an alternate hydrofoil configuration taken along the line 15 8—8 in FIG. 9.

FIG. 9 is a transverse section of the hydrofoil shown in FIG. 8 taken along line 9—9 thereof.

20 The device of the present invention utilizes the supporting members of a craft or vessel suspended in water to induct water into the craft for use in powering the craft by water-jet propulsion, thereby avoiding the addition of appendages beyond those supporting the craft for this purpose.

25 Referring now to FIG. 1 there is shown a craft 11 having attached to it hydrofoil members 12, 13, 14, and 15 which members are suitably affixed to the hull of the craft by fittings 18. The hydrofoil members are preferably depending from their support members 20, shown in FIG. 4, in a negative dihedral posture which provides

30 a change of angle of attack as the foil is turned about a vertical axis. The foil members and supports are in fixed relation to one another, with rotation of the supports 20 accomplished through the application of a selected torque applied via bell crank 22, in the manner disclosed in my U.S. Patent 2,823,636 issued February 18, 1958. A support bracket 23 is shown in greater detail in FIG. 5, FIG. 5 also disclosing that shaft 20 is continuous through housing 24 and terminates within collar 26.

35 40 Vessel or craft 11 is propelled by a water-jet propulsion means illustrated schematically at 28, which means may be of the type described in copending U.S. patent application Serial No. 20,897, filed April 8, 1960, or other similar jet propulsion means by which a propelling

45 force is produced by forcing water at high velocity through a jet nozzle. In the embodiment illustrated in FIGS. 1 and 4 water is inducted to a pump 30 via a conduit means 31 within hydrofoils 12, 13, 14, and 15 through inlets 32. A continuous passage is formed within or integral with the hydrofoils, supporting shafts 20, a plenum 33, pump 30 and jet 28. Shaft 20 is, as stated, rotatable substantially 360° by means of bell crank 22. Conduit members 34, 35, 36, and 37 are connected respectively to the hydrofoil members 14, 12, 13, and 15.

50 55 Water is conveyed to the conduit members from support members 20 via channel members 40 which are illustrated in greater detail in FIG. 5. As shown in FIG. 5, orifices 41 are provided in support members 20 permitting flow of fluid therethrough and into annular chamber 43 thence into their respective conduits. The flow of water from rotatably mounted support member 20 into annular chamber 43 may be other than through orifices as shown in FIG. 5, such as by providing vertical slots in support member 20 through which water may flow, with a limitation on permissible area of the orifices or slots being the strength requirement of member 20 to impart turning moment of the hydrofoil member with which it is associated.

60 65 70 Water is inducted into the hydrofoils, and such induction may be through inlets such as 32 at the end of the foil as shown at the left in FIG. 2 or in inlets along the

leading edge of the foil as shown at 45 in FIG. 9. In FIG. 2 the end of hydrofoil 14 is tapered such that the leading edge 46 thereof is of shorter length than the trailing edge 47, the forward motion of the craft being in the direction indicated by arrow 48. Inserted in inlet 32 to promote scooping or otherwise enhance the induction of water into the inlet are vanes 50 shown in FIGS. 2 and 3. It is within the scope of the present invention to have other means than vanes 50 inserted in the inlets, and also to have other configurations than the taper at 32, or to provide for induction of water at inlets along the top or bottom surfaces of the hydrofoils or along the trailing edges thereof, or a combination of the inlets mentioned.

Each of the journal boxes 40 in the embodiment of FIGS. 1 and 4 provides both structural strength and steadyng for the corresponding support member 20 as well as including the annular chamber 43 to convey water from the support member 20 into the respective conduit 34, 35, 36, or 37.

In FIG. 6, there is shown an alternate embodiment of the invention wherein craft 11 has attached to it forward hydrofoils 60 and 61 and aft hydrofoils 63 and 64. The forward hydrofoils extend under the vessel and pivot at 66. Hydrofoils 60 and 61 are rotatable about their longitudinal axis through bell cranks 68 and 69. In the embodiments of FIGS. 6 and 7, intake of water is effected through only the aft hydrofoils 63 and 64 which hydrofoils also provide substantially 65% of the support of the craft when planing on its hydrofoils. Hydrofoils 63 and 64 may have vanes 50 in their inlets along the leading edge thereof, as shown, or the leading edge may have perforations 45 such as those shown in FIG. 8. Where the leading edge has such perforations, a check valve member 72 may be inserted so that back pressure of the water will be prevented from causing the water to escape through the perforations 45 should part of either hydrofoil 63 or 64 come out of the water due to waves or maneuvers.

It will be appreciated that the intake of water may be effected through nacelles, not shown, positioned at the ends of hydrofoil support members within the concept of the invention.

In the embodiment of FIG. 6, control about the roll, pitch, and yaw axes is effected through a combination of rotation of forward hydrofoils 60 and 61 and actuation of control vanes 73, only one of which is shown on the aft hydrofoil surfaces. In the FIG. 6 embodiment, the ducts in hydrofoils 63 and 64 are shown supplying water to four jet devices, namely, 76 and 78 being supplied by hydrofoil 64, and 75 and 77 by hydrofoil 63.

The hydrofoils in the embodiments of the invention may perform several functions some of which are to serve as cantilever beams supporting the hull, to provide hydrodynamic control surfaces, to provide for the induction of water through scoops or other suitable means, and as water ducts per se to the water-jet engine intake. The basic rigidity and strength of the foil structure and the support function of the hydrofoils are all factors to be accommodated into a hydrofoil configuration most suitable to minimize torsion deflection which may cause undesirable changes in angle of incidence (attack) and result in control instability. The internal conduction or induction of water through the foil may be accomplished by conduits installed therein connected to the inner conduit of supports 20, or the passage in each hydrofoil may be integral with the hydrofoil itself, that is, with appropriate arrangement of the internal foil structure, to provide for improved or less disturbed flow of water.

The embodiment shown in FIG. 1 contains control stick means 80 for controlling the positioning of each of hydrofoil surfaces 12, 13, 14, and 15. Movement of the control stick is conveyed to the respective bell cranks attached to support members 20 through control box 81. Motion about the three axes of movement of the craft—

namely, the yaw, roll, and pitch axes is imparted in a manner similar to that described in my U.S. Patent 2,823,636 issued on February 18, 1958. Control stick motion may produce pitch motion of vessel 11 by rotating the 5 respective support members 20 to pivot hydrofoil surfaces 12 and 13 in a forward direction and 14 and 15 in a rearward direction. By such motion less lift is provided through foils 12 and 13 to depress the bow of craft 11. Turning moment about the roll axis is obtained by imparting 10 opposite motion to foils 12 and 13 and paralleling to them the foils 14 and 15, respectively. Motion about the yaw axis is obtained by moving the foils on one side of the vessel toward one another and the foils on the opposite side of the vessel away from one another, 15 providing turning or steering of the vessel.

Control of the embodiment shown in FIGS. 6 and 7 is effected through rotation of forward hydrofoils 60 and 61 and concurrent actuation of control surfaces 73. Turning moment about the yaw axis is obtained by imparting 20 opposite rotation to foils 60 and 61, i.e. turning the leading edge of one downward and of the other upward, and paralleling to them control surfaces 73. Thus, to make a turn to the right or starboard, hydrofoil 61 would be rotated with its leading edge turned upward, while control surface 73 would be rotated downward. Such rotation would in effect produce a pitch up due to the foils on the starboard side of the vessel which is complemented by an opposite moment imparted to companion foils and surfaces causing downward pitch to be exerted on the port side thereby resulting in a pure turn of the vessel to starboard. Motion about the pitch axis is obtained by rotating foils 60 and 61 in the same direction, that is, with the leading edges of each downward or upward, and imparting opposite rotation to control surfaces 73. 25 Motion about the roll axis is obtained by rotating hydrofoils 60 and 61 oppositely and rotating respective surfaces 73 in the opposite direction to the direction of rotation of the forward hydrofoil attached to the same side of the vessel.

In summary, there is provided by the present invention a unique use of support surfaces for a water craft to permit the craft to attain speeds in a seaway far exceeding those where a hull to which the surfaces are attached is partially immersed in the water. The support surfaces 40 induct water to provide for water-jet propulsion of the craft wherein such induction of water does not require the addition of any appendages to the craft. Additionally, the support surfaces provide for control of the craft about the three axes of movement. An important reduction in 45 underwater sound is also provided rendering a hydrofoil craft propelled by water-jet means substantially more difficult to detect than conventional craft.

Obviously many modifications and variations of the present invention are possible in the light of the above 50 teachings. It is therefore to be understood that within the scope of the appended claims the invention may be practiced otherwise than as specifically described.

I claim:

1. A water intake and ejection system for a craft of the hydrofoil type powered by water-jet propulsion comprising at least four hydrofoil support means rotatably mounted on said craft, control means connected to each of said support means for controlling movement of said craft about the pitch, yaw and roll axes while said craft is supported by said support means, water-jet propulsion means in said craft, conduit means in at least two of said support means for conveying water to said propulsion means, and said at least two support means being provided with inlets located in the respective surfaces thereof and communicating with said conduit means for introducing water into said conduit means through the inlets.
2. The system claimed in claim 1 wherein said inlets are positioned in said at least two support means in areas remote from said craft.
3. The system claimed in claim 1 wherein each of said

conduit means is integral with said support means corresponding thereto.

4. The system claimed in claim 3 wherein said support means are tapered at their extremities remote from said craft such that the leading edge of each support means is shorter in length than the trailing edge, said inlets being positioned at said extremities, and arcuate vane means in said inlets for directing water into said support means.

5. A water intake system for a craft of the hydrofoil type powered by water-jet propulsion comprising at least four hydrofoil support means for supporting said craft out of the water across which the craft travels, water intake means in at least two of said support means, said water intake means having inlets at positions remote from said craft, at least two of said support means being rotatable with respect to said craft, and means for rotating said rotatable support means whereby movement of said craft about selected axes may be controlled.

6. The system claimed in claim 5 wherein said support means having intake means therein are nonrotatable, and movable control surfaces in said nonrotatable support means to complement the action of the rotatable support means in providing for control of said craft.

7. A water intake system for a craft of the hydrofoil type powered by water-jet propulsion comprising at least four hydrofoil support means for supporting said craft out of the water across which the craft travels, water intake means in each of said support means, said intake means having inlets at positions remote from said craft,

each of said support means being rotatable with respect to said craft, and means for rotating said rotatable support means whereby movement of said craft about selected axes may be controlled.
